SAMUEL COHN, OF NEW YORK, N. Y., ASSIGNOR TO MANTLE MACHINERY & PATENTS COMPANY, OF NEW YORK, N. Y., A CORPORATION OF NEW YORK.

MANUFACTURE OF INVERTED MANTLES.

1,151,342.

Specification of Letters Patent. Patented Aug. 24, 1915.

Application filed April 17, 1912. Serial No. 691,425.

To all whom it may concern:

Be it known that I, SAMUEL COHN, a resident of New York city, in the county and State of New York, have invented a new and useful Improvement in the Manufacture of Inverted Mantles, of which the following is a full, clear, and exact description, reference being had to the accompanying drawings, forming part of this specification, in which—

Figures 1, 2, 3 and 4 are perspective views illustrating a series of steps taken upon a mantle blank. Fig. 5 shows the first step in my process. Fig. 6 shows the shape of the mantle while being sewed or darned. Figs. 7 and 8 are, respectively, a perspective view and an end elevation of the finished mantle. Fig. 9 is a sectional side elevation of the machine on the line IX—IX of Fig. 10, showing the operating parts of the darning machine which I prefer to employ. Fig. 10 is a top plan view of the operating plate and ratchet disk. Figs. 11 and 12 are sectional detail views on the line XI—XI of Fig. 10, showing different positions of the plate reciprocating mechanism. Fig. 13 is a central vertical cross-section of the ratchet disk. Fig. 14 is a top plan view of the mantle showing the stitch design and arrangement.

My invention relates to the manufacture of inverted mantles and is designed to avoid the difficulties incident to the thick mass of longitudinally extending folds which are gathered toward the center at the closed end.

In accordance with my invention, the end of the mantle is gathered, but the folds are not pulled together and compacted in longitudinal form. On the contrary a hole is left of considerable size at the center of the mantle, the gathered portions extending inwardly in a transverse direction toward this hole; and by means of impregnated thread, the hole is mechanically darned so as to close it with the same material as that of the mantle. In carrying out the invention, a circular row of stitches is preferably taken around the hole to fix the threads in position and the darning is then proceeded with to fill up the hole.

In the drawings, Fig. 1 represents the ordinary blank 2 cut from the hollow or knitted and impregnated web with the shirring string 3 therein. Fig. 2 shows the

blank secured to the mantle ring 4 by the cord 5. Fig. 3 shows the mantle blank then turned right side out; 6 being the legs of the mantle ring. The portion carrying the draw string 3 is then pushed down through the hole in the ring 4 into the position shown in Fig. 4. The lower shirred and partly compacted end is then pulled together and tied around the tapered part of a pin 7, shown in Fig. 5. After tying the draw string or cord, the tied end is then forced down on to the cylindrical part 8 of the pin, thus fixing the size of the hole at the shirred end.

The blank is now ready for the machine 70 operation, and I will now describe a preferred form of machine shown in Figs. 9 to 13, inclusive, for darning and stitching the blank. The machine may take the form of an attachment to an ordinary sewing machine, 9 representing the bed plate of the sewing machine, having side guides 10, 10 to receive a reciprocating plate 11, which has a circular opening receiving the ring-shaped portion 12 of a ratchet disk 13 provided with ratchet teeth 14 on its bottom surface. This ratchet disk also has a central hole, shown at 15, and is arranged to turn within the hole in the reciprocating plate 11.

The reciprocating plate, in the form shown, is provided with a rear guide 16, receiving a vertically movable transverse catch plate 17, the projecting ends of which enter the wider recesses 18 in the side guides. When the catch plate is in lowered position, it allows the reciprocating plate to move back and forth with a limited movement. When it is raised, the plate, disk and guide may be drawn out endwise from the guides. The ratchet disk turns on the bed plate 95 above the needle hole 19 therethrough, which needle hole is normally at one side of the opening through the disk.

The mantle blank prepared as above described is forced within the circular flange of the ratchet disk with the hole in the mantle concentric with the hole in the disk. The legs of the refractory ring for the mantle are guided and supported by a ring 20 secured to the depending frame portion 21 of the machine; and instead of using a presser foot with the needle 22, I preferably employ a spiral spring 23 surrounding the needle.

I provide mechanism for intermittently 110

and rapidly turning the ratchet disk, and I may reciprocate its carrying plate by hand. I preferably carry out both of these movements by machine connections, however, and for this purpose I have shown the arm 24, having a forked end engaging an eccentric 25. This feed arm 24 is actuated by a rock arm projecting from shaft 26. A bracket 27 secured to the feed arm 24 has an arm 28 carrying a shaft 29, to which are secured a ratchet wheel 30 and a cam disk 31. A pawl 32 pivoted to rock arm 33 secured to shaft 26 is held in engagement with the ratchet wheel 30 by a spring 34 secured to bracket 27. The cam disk 31 acts upon a depending pin 35 on a downwardly extending leaf spring 36 secured to feed plate 37 mounted on the feed arm. This spring 36 has a pawl tooth 38 moving up through a hole in the feed plate, and also in the bed plate so as to coöperate with a tooth 39 projecting downwardly from the reciprocating plate 11. A two-armed coiled spring is fastened to one of the bed plate guides, as shown at 40 in Fig. 10, one arm of this spring engaging a pin 41 on the guide, while the other arm 42 engages the edge of the reciprocating plate and tends to force it constantly toward the right.

30 The operation of these parts is as follows: At each advance of the feed arm 24 the ratchet wheel 30 and the cam disk 31 move therewith and the pawl 32 moves to the right until it reaches and engages a succeeding tooth of the ratchet wheel. Upon the return of the feed arm and pawl 22, the latter will cause the ratchet wheel and cam disk to rotate one unit of movement. This rotation occurs at each stitch period of the machine. While the cam disk progresses, the pin 35 on spring 36 will ride on a raised portion of the cam disk during a complete stitch period, and then will ride on a depressed portion through a like period.

40 When the pin rides on the raised part of the cam disk, the pawl 38 will be in the path of pawl 39. Under these conditions, as the feed arm moves to the left, the reciprocating plate will be moved in the same direction. At about this time, the needle will descend and form a stitch as shown at 43 in Fig. 14. As the needle ascends the feed arm is lowered by the eccentric 25, which disengages the pawl 38 from the tooth 39,

50 and by the time the needle is lifted the feed arm has reached its extreme position to the right. Before the needle has fully ascended, and at the time when the feed arm has been lowered by the eccentric for such disengagement, the reciprocating plate 11 will have been returned by the spring arm 42. By this time the feed arm will have reached its extreme right hand position, the pawl 22 will have engaged a successive tooth in the ratchet wheel and carried it one unit of

movement, bringing a depression in the cam disk in contact with a depending pin 35. The continued operation of the machine at this point will cause the following action: The feed arm will start to move to the left; 70 the depending pin 35 riding on a depression of the cam disk will cause the pawl to clear the tooth 39, and hence the reciprocating plate will not be moved during the next step. The needle will descend and form a 75 cross stitch as at 44 by the time the feed arm has reached its extreme left-hand position. As the needle ascends the feed arm will begin its movement to the right, bringing into operation the pawl 32, which will again move one of the raised portions of the cam disk underneath the depending pin 35. At this point the pawl 38 will have engaged tooth 39, and as the needle is now descending, the reciprocating plate will again be 80 moved in the left-hand direction, and at this time the point 45 of the mantle will be brought underneath the needle owing to the rotation of the mantle-holding device. A continuation of these operations will form 85 stitches in the design shown in Fig. 14. The hole in the mantle is thus darned and filled with cross stitches or threads. After the darning process, the machine may be stopped and the blank removed and the after treatments thereon are the same as those generally used.

The advantages of my invention result from the darning of the hole left in the end of the mantle, and the doing away with the longitudinal folds drawn together at the center of inverted mantles. By the machine darning, a larger hole may be left than in hand darning, and the use of the spring for the needle keeps pressing down the plaits 100 or folds of the mantle, so as to make the fabric even and symmetrically disposed. It is evident, that the larger the hole, the finer and thinner will be the plaits around it at the dome end. Lighter thread may be used 105 than in hand darning as the fabric is held together by the shirring thread before the darning operation is carried out. The use of this invention has shown that the material at the dome end of the mantle will be 110 very evenly distributed and it will be almost as thin and even as the rest of the fabric.

Instead of closing the hole by darning it with a series of stitches, I may cover the hole with a patch, which is a patch of 115 impregnated material which will be stitched in place by a circular row of stitches.

Many other variations may be made in the form of the machine and the steps of the process, without departing from my invention.

I claim:

1. In the manufacture of inverted mantles, the steps which consist in permanently securing one end of a tubular mantle 120

blank to a supporting ring, turning the blank inside out through the ring, contracting the other end of said blank by forming shirrs therein, and securing said shirrs, 5 compacting the terminals of the shirrs by enlarging the opening through the reduced end of the blank to a predetermined size, and closing the said opening of predetermined size by a fabric material extending 10 across the same.

2. In the manufacture of inverted mantles, the steps consisting in securing one

end of a tubular mantle blank to a ring, turning the mantle inside out, contracting the opposite end by shirring, while leaving 15 a hole through said end, increasing the size of the hole, and at the same time compacting the shirrs and cross-darning the hole.

In testimony whereof, I have hereunto set my hand.

SAMUEL COHN.
